TREATING NATURAL OILS AND FATS

Harold D. Hoffman, Park Ridge, and Albert H. Zeigler, Evanston, Ill., assignors to Armour and Company, Chicago, Ill., a corporation of Illinois

No Drawing. Application November 22, 1940,
Serial No. 366,706

7 Claims. (Cl. 260—418)

This invention relates to a method for treating natural oils and fats.

In the treatment of natural oils and fats where the material is split to separate the fatty acids and the fatty acids are subsequently distilled, considerable difficulty has been encountered by reason of impurities within the fats and oils which tend to induce pitch formation and low distillate yields. With some stocks, there are found to be present certain ingredients which bring about emulsion difficulties in the splitting operation and greatly reduce the final yield by distillation while also resulting in a product of poor color. It is also found that in the treating operation some damage is done to the double bond structure of the fatty acid which, in the final distillation step, tends to produce polymerization of the more unsaturated components.

In the treating methods now employed prior to the distillation step, it is customary to hydrolyze the material either by autoclaving or by twitchellizing. In autoclaving an oil, the usual procedure is to add a catalyst, which may be zinc oxide, calcium oxide or caustic soda, etc. However, the amount of alkali metal used for this process is relatively small and is not sufficient to react with all of the fatty acids which result from the splitting operation. The catalyst is used only in an amount sufficient to promote the hydrolyzation. If a sufficiently high temperature is employed and the operation carried on for a sufficient length of time, the catalyst may be entirely omitted. As already stated, the above treating operations now employed result in a somewhat inferior product, in a relatively low yield in the final distillation step and in a reduction or loss of some unsaturates present in the original stock.

An object of the present invention is to combine with the distillation or fractional distillation step an earlier treating operation which results in a better distillate yield, a product of better color, and with less destruction of unsaturates in the distillation operation. While in some respects, the two main steps of the new process are old, the combination thereof in the manner which will be described result in extremely important and new results.

Instead of autoclaving in the presence of catalysts or twitchellizing the natural oils or fats, we find that far better results can be obtained by completely saponifying with an alkali the oils and fats as the first step, the saponification being preferably carried on in an open kettle and under atmospheric pressure, the step being very much that in which ordinary soap is made. After the

saponification of the mass, the soap is acidulated to liberate the fatty acids and the fatty acids are then subjected to fractional distillation.

Following the first step of saponification, we find that the product can be improved and better yields obtained if the resulting soap is grained with salt or with alkali in a manner similar to the customary method of settling a soap during the manufacture of soap. The lye (lower phase) is removed and water and salt added to the soap and one or more similar washes repeated. The impurities are more soluble in salt solution than is the soap and effective separation results from this process. The settled soap is removed, acidulated, and the fatty acids stock subjected to distillation.

The product resulting from the distillation has a much better color and the yields are substantially greater than those obtained by the old methods as will be shown later by reference to specific examples. Further, in the treatment of stocks containing a large amount of unsaturated fatty acids, and where it is desired to obtain in the final product a high yield of the unsaturated fractions, the new method considerably increases the yield of such product over that heretofore obtained.

By way of example, the application of the process to low grade fats, such as cotton seed and soybean oil foots, may be discussed in detail. Cotton seed foots, for example, are normally handled in one of the following methods: the foots are acidulated and the resulting black stock subjected to distillation without treatment. Usually the still "bottoms" are subsequently hydrolyzed and the resulting black stock subjected the second time to distillation. In an alternative method, the foots are hydrolyzed, either by autoclaving or by twitchellizing, and the resulting split stock subjected to distillation. In either of these normal methods of preparing and distilling the acids from cotton seed foots, the overall distillation yield has been of the order of 88 percent. The low yield is due to impurities. Cotton seed foots contain very substantial amounts of impurities which are found to induce pitch formation.

It is well known that distillation yield is related to the efficiency of the splitting or hydrolyzing of the oils. The methods heretofore used result in splits of 95 percent or thereabouts. It is generally known that raising the split to about 97 to 98 per cent will increase the overall distillation yield. Obviously the unsplit portion is not distillable and this portion remains as a component of the pitch. However, the amount of

pitch that results from distillation is always greater than that accountable by the unsplit portion of the feed stock and it is generally assumed that this is due to copolymerization of some of the fatty acid with the unsplit oil.

In the treatment of cotton seed foots, we have found a substantial improvement both in distillation yield and quality of the distillate, if the following steps are carried out: cotton seed foots are completely saponified with caustic soda at atmospheric pressure. The resulting soap is grained with salt or with alkali in a manner similar to the customary method of settling a soap kettle during the manufacture of soap. The lye (lower phase) is removed and water and salt added to the soap; and one or more similar washes repeated. The washings are found to remove a substantial portion of the impurities which are more soluble in salt solution than is the soap. The settled soap is removed, acidulated, and the prepared black stock subjected to distillation. The "split" on the black stock prepared in this fashion will run around 98 to 99 percent, which is substantially better than that secured by the other methods now in use.

The salting or graining operation removes proteins, mucilaginous substances, oxidized fatty acids, coloring matter and other impurities.

The distillation yield on the black stock prepared as above set forth is 95 percent, and the quality of the distillate is measurably better than that obtained by the other methods. For example, in fractionally distilling cotton seed fatty acids, we find that the proposed method produces a palmitic acid fraction having a color reading of 4.4R, 20Y, through 1 1/4" on the Lovibond scale compared to 30R, 100Y by the previous methods.

If, in the above process, the graining step is omitted, we find that there is a reduction in the yield and a lowering in the quality of the distillate. For example, cotton seed foots that were completely saponified but not grained showed a distillation yield of only 92 percent, as compared with a yield of 95 percent where the graining step was employed. Likewise, the color of the C₁₈ unsaturated fraction of the stock which was not grained was 3.5R, 9Y. This was considerably darker than the 1.2R, 5Y that was obtained on grained stock.

As a second example of the process, the application to highly unsaturated oils, such as sardine oil and menhaden oil, may be set forth in detail. In the treatment of highly unsaturated oils such as sardine oil, the prime object is to obtain a fraction which possesses very high unsaturation and hence can be used advantageously in the paint and resin industry. The important consideration is to obtain the highest possible yield of fatty acid distillate having the desired degree of unsaturation. It is also desired to obtain such a distillate of the best possible color.

In the methods now employed, the first step is to hydrolyze or split the fish oil by autoclaving or twitchellizing. In autoclaving, the usual procedure is to add a catalyst such as zinc oxide, calcium oxide, caustic soda, etc. The amount of the alkali metal used is kept as low as possible, it being used only in sufficient amounts to promote hydrolysis. Where a sufficiently high temperature is had and sufficient length of time is employed, the catalyst may be entirely omitted.

When sardine oil is split by either of these conventional methods, i. e. autoclaving or twitchellizing, and the resulting acids subjected to distillation, it is found that an iodine balance on

the total products resulting from distillation falls considerably short of the iodine value of the acids in the original oil. In other words, considerable destruction to the carbon-to-carbon double bonds has resulted along the way.

We have found that when sardine oil is completely saponified in a kettle with caustic soda in a manner similar to that in which ordinary soap is made and the soap is then acidulated to liberate the fatty acids from the soap, and these fatty acids are then subjected to distillation, the products resulting from the distillation show a much higher iodine balance as compared to the original starting material than is the case when the sardine oil is hydrolyzed according to methods previously employed.

Under the old methods we obtained a 35 percent yield of fatty acids, having an iodine value of 240 when sardine oil, having been either autoclaved or twitchellized, was fractionally distilled. Under the new method of preparing the fatty acid feed stock before distillation, the yields of fatty acid distillate having an iodine value of 240 jumped to 50 percent. When the bottoms were subjected to a redistillation process, there was recovered from it 31.8 percent of fatty acid having an iodine value of 241. An overall yield of 55.7 percent having an iodine value of 236 was obtained.

We are not able to set forth positively a reason for the unexpected improvement in yield of the high iodine fraction. It may be due to factors as to which we have no information. We are inclined to attribute the improvement to the lack of damage to the carbon-to-carbon double bonds during the splitting operation. Our experiments indicate that autoclaving high iodine oil, such as sardine oil, does bring about some kind of damage to the double bond structure of the fatty acid. The higher the pressure at which autoclaving is carried on, the greater the damage. In the case of twitchellizing, damage appears to lie in the sulfonation of the double bond. Although the resulting split acids may appear to be undamaged, as indicated by the iodine value, the inferior distillation yield suggests that some sulfonation may have occurred and that this organic sulfate linkage may, at the temperature of distillation, produce polymerization of the more unsaturated components.

In addition to the great improvement in yield of the high iodine fraction, the color of the resulting distillate is found to be much better than that obtained under the old methods.

The surprising increase in yield of distillate can hardly be explained on the ground of difference in splits obtained by the new method. Since the split on sardine oil twitchellized was 98 percent, compared with the split on the saponified oil, which was 98.7 percent, we believe that the theory suggested above may be the true explanation.

A third example of the process is the application thereof to refractory oils such as, for example, refuse palm oil. This oil is discarded oil obtained from tin platers. Tin platers use large quantities of palm oil to quench tin plate before exposure of the hot metal to air. The temperatures at which the oil is heated are upwards of 500° F. and they cause considerable damage to the oil. Damaged oil is constantly removed and the bath replenished with fresh palm oil. In an effort to obtain salvage value from the vast quantity of damaged palm oil available, attempts have been made to hydrolyze it and subject the result-

ing fatty acids to distillation. Extreme difficulties have been encountered in splitting or hydrolyzing such oil due to extremely persistent emulsions which result from the usual methods of splitting. Various expedients have been used to surmount this difficulty, including treatment with fuming sulfuric acid, centrifuging of the emulsion, etc. The results have been far short of the desired results.

Unless the emulsion is broken, it is impossible to separate the fatty acids from the glycerine. Furthermore, it is impossible to separate catalysts and mineral acids from the fatty acid feed stock. The iron and tin which contaminate the refuse palm oil cannot be removed from the feed stock. Further, when the feed stock which has not been completely freed from water emulsion and the above objectionable impurities, is fed to the still, blocking of the heaters almost invariably occurs and both yield and quality of the distillate are disappointing. Under the circumstances, yields of 50 percent have heretofore been felt satisfactory, and seldom has a yield exceeded 70 percent.

When under the present process the refuse palm oil is completely saponified with caustic soda and grained in the manner well known to the soap manufacturer, the wash waters remove very substantial quantities of oxy-acids, which we find are responsible for the above emulsion difficulties, and they remove also substantial quantities of the metallic impurities. Soaps of oxy-fatty acids are quite soluble in brine solution as contrasted with the soaps of normal fatty acids which are completely salted out of solution. The assembly of fatty acids as solubles in the washing operation enables the complete separation of the fatty acids to be accomplished during the subsequent acidulation of the soap. The metallic impurities, such as iron and tin, are quite completely removed in the acidulation, since no water is retained in the fatty acid stock.

When the fatty acid stock obtained from the above method is subjected to distillation, we obtain yields of the order of 85 percent as contrasted with the usual 50 to 70 percent obtained by the other methods of processing now in use. The quality of the product is improved, the color of the distillate being decidedly better than that of the distillate obtained by the old methods. Thus there is a substantial improvement both in the yield and quality. The invention is applicable to tall oil and to a number of other highly impure oils.

The above examples are believed to be exemplary of the steps to be followed and the results which may be obtained through the new combination of steps, such combination including complete saponification and acidulation, together with the final fractional distillation operation. Similar benefits may also be obtained with straight distillation. We prefer, however, to employ in the combination the salting step which is important in reducing and eliminating impurities which interfere with the subsequent high distillation yield.

While in the foregoing specification we have set forth certain specific steps and certain specific exemplary operations for the purpose of illustrating the invention, it will be understood that great variation may be made in such steps and in the

substitution of chemical equivalents, without departing from the spirit of our invention.

We claim:

1. In a process for treating natural oils and fats, the steps of saponifying the mass with an alkali to form soap, graining the soap with an aqueous solution of a substance of the class consisting of salts and alkalies, drawing off the solution and the solubles therein and recovering the settled soap, acidulating the settled soap to free the fatty acids, and distilling the fatty acids.
2. In a process for treating natural oils and fats, the steps of completely saponifying the mass with caustic soda and at atmospheric pressure, 15 graining the resulting soap with an aqueous solution of the substance of the class consisting of salts and alkalies, separating the solution and the soap, acidulating the soap to free the fatty acids, and distilling the fatty acids.
3. In a process for treating low grade fats of a class consisting of cotton seed and soy-bean oil oil foots, the steps of completely saponifying with an alkali the fats, graining the resulting soap with an aqueous solution of a substance of the class consisting of salts and alkalies, separating the solution and the soap, acidulating the soap to free the fatty acids, and distilling the fatty acids.
4. In a process for treating low grade fats of a class consisting of cotton seed and soybean oil foots, the steps of completely saponifying the fats with caustic soda and at atmospheric pressure, graining the resulting soap with an aqueous solution of a substance of the class consisting of salts and alkalies, withdrawing said solution, recovering the settled soap and acidulating it to liberate the fatty acids, and distilling the fatty acids.
5. In a process for treating highly unsaturated fish oils, the steps of completely saponifying the oil with an alkali at atmospheric pressure, graining the resulting soap with an aqueous solution of a substance of the class consisting of salts and alkalies whereby the soap and the solution form two phases, with the solution and the materials soluble therein in the lower phase, withdrawing the lower phase, recovering the settled soap and acidulating it to free the fatty acids, and distilling the fatty acids.
6. In a process of the character set forth for treating refuse palm oil, the steps of completely saponifying the oil with an alkali, graining the resulting soap with an aqueous solution of a substance of the class consisting of salts and alkalies whereby the soap and the solution form two phases, with the solution and the materials soluble therein in the lower phase, removing the lower phase, acidulating the settled soap to free the fatty acids, and distilling the fatty acids.
7. In a process of the character set forth for treating refuse palm oil, the steps of completely saponifying the oil with caustic soda and at atmospheric pressure, graining the resulting soap with an aqueous solution of a substance of the class consisting of salts and alkalies whereby the soap and the solution form two phases, with the solution and the materials soluble therein in the lower phase, removing the lower phase, washing the soap, acidulating the settled soap to liberate the fatty acids, and distilling the fatty acids.
